UNITED STATES PATENT OFFICE

JOHN C. HANRAHAN, OF LOS ANGELES, CALIFORNIA

WATER-TUBE STEAM BOILER

Application filed November 1, 1926. Serial No. 145,553.

My invention relates to water tube steam boilers and is an improvement over the invention of my Patent 1,552,296, dated September 1, 1925, for a steam boiler. The boiler 5 of my present invention is of substantially the same shape as that of my patent but I eliminate the intermediate combustion wall and the central water drum. I also eliminate the water legs and introduce a line of large 10 sturdy tubes connected from the lateral steam and water drums to the mud drum at the base, these forming in a sense ribs and being termed rib tubes, such tubes are partly embedded in the refractory composition of the 15 furnace walls.

An object of my invention is the construction of an internally fired and water tube boiler in which the furnace is enclosed by the tubes, such tubes leading to different drums 20 and to a steam drum at the top.

Another object of my invention is having refractory walls from which the heat rays are reflected across the path of the escaping gases and aid in bringing such gases to a high temperature, giving a more perfect combustion. 25

Another object of my invention is to prevent the breaking down of the refractory furnace walls through excessive temperature, this being done by utilizing the rib tubes 30 which have circulating water therein, these tubes protecting and cooling the furnace wall as well as rapidly heating the water for generating steam.

Another object of my invention is the supporting of a plurality of steam and water drums and a steam drum at the top without the use of intermediary supports, hangers, rollers, or the like. The various tubes connecting the mud drum, the lateral steam and water drums, and the steam drum, give the support necessary and thus allow for equalizing expansion of the metal parts of the 40 boiler.

My invention will be more readily understood from the following description and drawings, in which:

Figure 1 is a transverse vertical section through the boiler,

Fig. 2 is a longitudinal section taken on

the line 2—2 of Figure 1 in the direction of the arrows,

Fig. 3 is a detailed horizontal section on the line 3—3 of Figure 1, showing the construction of furnace walls and rib tubes, 55

Fig. 4 is a perspective detail of the perforated baffle.

The mud drum 1 is centrally supported on the floor 2 of the furnace and the series of water tubes 3 extend upwardly at an angle 60 forming a substantially V-shaped nest of tubes, these tubes being connected at their upper ends with a pair of steam and water drums 4, for the generation of steam from the water. Another set of tubes 5 lead upwardly from the steam and water drums and connect to the steam drum 6. A series of relatively large rib tubes 7 are connected to the steam and water drums, as designated by the numeral 8, on their lower outward side 65 and lead downwardly, being connected to the mud drum adjacent the bottom as indicated by the numeral 9. The grates 10 of the furnace are on opposite sides of the mud drum 9 and preferably adjacent the top of said drum 70 running lengthwise of the furnace. Perforated baffle walls 11 form a V-shaped structure lengthwise of the mud drum 1 and the steam and water drums 4, these walls preferably resting on the upper or inner row of 75 tubes 3. A series of equalizing tubes 12 are arched between the drums 4 designed to have their ends connected to the drums at substantially the line of the water level, and a top perforated arch 13 extends between the 80 drums 4, being supported on the tubes 12. 85

The furnace structure is built up by having side walls 14 and a roof section 14'. The rib tubes are preferably encased to half diameter in a fire resisting composition below 90 the grates and thence continuing above the side of the grates. Insulating walls 17 connect the side walls with the steam and water drums 4.

A steam pipe 18 is connected to the top of 95 the steam drum and pipes 19 connect with the mud drum and the steam drum and have a water gauge and column or the like 20 fitted therein.

In order to blow the sediment from the 100

mud drum I employ an inlet and blow-off pipes 21 and 22, connected to the opposite ends of the drums adjacent the base, by this means utilizing feed-pump water pressure the mud may be cleared out of the drum or any sludge that accumulates there. One of these pipes will also be utilized with the feed water.

The operation of the improved boiler is substantially as follows. Fuel 23 is burned on the grates 10, or gas, oil or pulverized fuel is projected above the grates into the chambers defined by the banks of tubes 3 and the walls 14. These chambers may be called "initial combustion chambers" as most of the combustion takes place therein. The unburnt fuel, air and products of combustion then pass between the tubes 3 and through the perforations in the perforated walls 11, entering the chamber 25 which is between the banks of tubes. This chamber may be called a "secondary combustion chamber." It will be noted that in this chamber, two streams of partly burnt fuel, air and products of combustion meet, and the effect of their meeting is to produce a whirling. The effect of the whirling is to bring the unburnt fuel into contact with the available oxygen, thus reviving combustion in this chamber and completing the combustion. The products of combustion then pass upwardly out of the top of this chamber, passing between the drums 4 and the equalizing tubes 12, through the perforations in the perforated arch 13 and finally striking against the steam drum or super-heating drum 6. The products of combustion are confined about the steam or super-heating drum 6 by an outer casing 27, and pass through a longitudinal passage 28 extending rearwardly of the steam drum to be discharged through a stack 29. The water, on being heated within the tubes 3, rises therein, flowing into the drums 4, and in a similar manner water rises from the mud drum 9 through the rib tubes 7 up to the drums 4. The steam generated within the drums 4 is carried therefrom through the pipe 5 to the steam drum 6 where it may be dried out and super-heated, being out of the presence of its liquor, and discharged into the steam pipe.

From the above described construction and description of the operation, it will be appreciated that the improved boiler provides three substantially equal sized combustion chambers, two of which act as initial combustion chambers within which most of the fuel is burned, and the third chamber constituting a secondary combustion chamber is so arranged that the gases from the initial combustion chambers will flow into it and meet to revive and complete the combustion. The combustion of fuel being practically complete in the boiler, the efficiency of the boiler is quite high. Furthermore, as it is possible for flame indicated at 24 to circulate about the tubes 3 be-

fore passing into the chamber 25, these tubes will be heated over their entire surfaces. In addition to the tubes 3 there are exposed surfaces on the rib tubes 7 which are heated, and also exposed surfaces on the drums 4 and 9 which serve to transmit heat to the water for the generation of steam. The embedded portions of the rib tubes 7 also receive a great amount of heat from the refractory walls 14 and in a similar manner the drums where they contact with the refractory walls will receive a great deal of heat from these walls.

Various changes may be made in the principles of my invention without departing from the spirit thereof, as set forth in the description, drawings and claims.

I claim:

1. A water tube steam boiler comprising a mud drum, two banks of tubes connected to the mud drum and divergently extending upward therefrom, two steam and water drums arranged above the mud drum, one steam and water drum being connected to one bank of tubes and the other steam and water drum being connected to the other bank, means providing walls connecting each steam and water drum to the mud drum, said banks of tubes serving to divide the space between the drums and walls into three chambers, the chambers between the banks of tubes and the adjacent walls constituting initial combustion chambers and the chambers between the banks of tubes constituting a secondary combustion chamber, there being passages between the tubes of each bank permitting fuel and the products of combustion to pass therethrough from the initial combustion chambers into the secondary combustion chamber and to meet therein in opposition and revive or complete the combustion before passing upwardly between the steam and water drums, and a steam or super-heating drum arranged above the secondary combustion chamber in the path of the products of combustion issuing therefrom and connected to the steam and water drums.

2. A water tube steam boiler comprising a mud drum, two banks of tubes connected to the mud drum and divergently extending upward therefrom, two steam and water drums arranged above the mud drum, one steam and water drum being connected to one bank of tubes and the other steam and water drum being connected to the other bank, means providing walls connecting each steam and water drum to the mud drum, said banks of tubes serving to divide the space between the drums and walls into three chambers, the chambers between the banks of tubes and the adjacent walls constituting initial combustion chambers and the chambers between the banks of tubes constituting a secondary combustion chamber, there being passages between the tubes of each bank permitting fuel and the products of combustion to pass

- therethrough from the initial combustion chambers into the secondary combustion chamber and to meet therein in opposition and revive or complete the combustion before passing upwardly between the steam and water drums, and rib tubes connecting the steam and water drums to the mud drum, said rib tubes being exposed to the interior of the initial combustion chambers.
3. A water tube steam boiler comprising a mud drum, two banks of tubes connected to the mud drum and divergently extending upward therefrom, two steam and water drums arranged above the mud drum, one steam and water drum being connected to one bank of tubes and the other steam and water drum being connected to the other bank, means providing walls connecting each steam and water drum to the mud drum, said banks of tubes serving to divide the space between the drums and walls into three chambers, the chambers between the banks of tubes and the adjacent walls constituting initial combustion chambers and the chambers between the banks of tubes constituting a secondary combustion chamber, there being passages between the tubes of each bank permitting fuel and the products of combustion to pass therethrough from the initial combustion chambers into the secondary combustion chamber and to meet therein in opposition and revive or complete the combustion before passing upwardly between the steam and water drums, and equalizing tubes connecting the steam and water drums across the top of the secondary combustion chamber between which the products of combustion from the secondary combustion chamber may pass.
4. A water tube steam boiler comprising a mud drum, two banks of tubes connected to the mud drum and divergently extending upward therefrom, two steam and water drums arranged above the mud drum, one steam and water drum being connected to one bank of tubes and the other steam and water drum being connected to the other bank, means providing walls connecting each steam and water drum to the mud drum, said banks of tubes serving to divide the space between the drums and walls into three chambers, the chambers between the banks of tubes and the adjacent walls constituting initial combustion chambers and the chambers between the banks of tubes constituting a secondary combustion chamber, there being passages between the tubes of each bank permitting fuel and the products of combustion to pass therethrough from the initial combustion chambers into the secondary combustion chamber and to meet therein in opposition and revive or complete the combustion before passing upwardly between the steam and water drums, and equalizing tubes connecting the steam and water drums across the top of the secondary combustion chamber between which the products of combustion from the secondary combustion chamber may pass.
5. A water tube steam boiler comprising a mud drum, two banks of tubes connected to the mud drum and divergently extending upward therefrom, two steam and water drums arranged above the mud drum, one steam and water drum being connected to one bank of tubes and the other steam and water drum being connected to the other bank, means providing walls connecting each steam and water drum to the mud drum, said banks of tubes serving to divide the space between the drums and walls into three chambers, the chambers between the banks of tubes and the adjacent walls constituting initial combustion chambers and the chambers between the banks of tubes constituting a secondary combustion chamber, there being passages between the tubes of each bank permitting fuel and the products of combustion to pass therethrough from the initial combustion chambers into the secondary combustion chamber and to meet therein in opposition and revive or complete the combustion before passing upwardly between the steam and water drums, and equalizing tubes connecting the steam and water drums across the top of the secondary combustion chamber between which the products of combustion from the secondary combustion chamber may pass, and a steam super-heating drum arranged above said equalizing tubes and connected to the steam and water drums against which the products of combustion may strike after passing between the equalizing tubes.
6. A water tube steam boiler comprising a mud drum, two banks of tubes connected to the mud drum and divergently extending upward therefrom, two steam and water drums arranged above the mud drum, one steam and water drum being connected to one bank of tubes and the other steam and water drum being connected to the other bank, means providing walls connecting each steam and water drum to the mud drum, rib tubes connecting each steam and water drum to the mud drum, said banks of tubes serving to divide the space between the drums and walls into three chambers, the chambers between the banks of tubes and the adjacent walls constituting initial combustion chambers and the chamber between the banks of tubes constituting a secondary combustion chamber, there being passages between the tubes of each bank permitting gases to pass therethrough from the initial combustion chamber and to meet therein in opposition and revive or complete the combustion before passing upwardly between the steam and water drums, and equalizing tubes connecting the steam and water drums across the top of the secondary combustion chamber between which the products of combustion from the secondary combustion chamber may pass.

chamber into the secondary combustion chamber and to meet therein in opposition and revive or complete the combustion before passing upwardly between the steam and water drums.

5 7. A water tube steam boiler comprising a mud drum, two banks of tubes connected to the mud drum and divergently extending upward therefrom, two steam and water drums arranged above the mud drum, one steam and water drum being connected to one bank of tubes and the other steam and water drum being connected to the other bank, means providing walls connecting each 10 steam and water drum to the mud drum, rib tubes connecting each steam and water drum to the mud drum, said banks of tubes serving to divide the space between the drums and walls into three chambers, the chambers between the banks of tubes and the adjacent 15 walls constituting initial combustion chambers and the chamber between the banks of tubes constituting a secondary combustion chamber, there being passages between the 20 tubes of each bank permitting gases to pass therethrough from the initial combustion chamber into the secondary combustion chamber and to meet therein in opposition and revive or complete the combustion before 25 passing upwardly between the steam and water drums, the opposed sides of the banks of tubes being covered by a perforated wall.

30 8. A water tube steam boiler comprising a mud drum, two banks of tubes connected to the mud drum and divergently extending upward therefrom, two steam and water drums arranged above the mud drum, one steam and water drum being connected to one bank of tubes and the other steam and water drum being connected to the other bank, means providing walls connecting each steam and water drum to the mud drum, rib tubes connecting each steam and water drum to the mud drum, said banks of tubes serving to 35 divide the space between the drums and walls into three chambers, the chambers between the banks of tubes and the adjacent walls constituting initial combustion chambers and the chamber between the banks of tubes constituting a secondary combustion chamber, there being passages between the tubes of each bank permitting gases to pass 40 therethrough from the initial combustion chamber into the secondary combustion chamber and to meet therein in opposition and revive or complete the combustion before passing upwardly between the steam and water drums, and a steam super-heating drum arranged above the secondary combustion chamber in the path of the products of 45 combustion issuing therefrom and connected to the steam and water drums.

50 9. A water tube steam boiler comprising a mud drum, two banks of tubes connected to the mud drum and divergently extending upwardly between the steam and water drums, and a steam super-heating drum arranged above the secondary combustion chamber in the path of the products of combustion issuing therefrom and connected to the steam and water drums.

55 10. A water tube steam boiler comprising a mud drum, two banks of tubes connected to the mud drum and divergently extending upwardly between the steam and water drums, and a steam super-heating drum arranged above the secondary combustion chamber in the path of the products of combustion issuing therefrom and connected to the steam and water drums.

60 11. A water tube steam boiler comprising a mud drum, two banks of tubes connected to the mud drum and divergently extending upwardly between the steam and water drums, and a steam super-heating drum arranged above the secondary combustion chamber in the path of the products of combustion issuing therefrom and connected to the steam and water drums.

65 12. A water tube steam boiler comprising a mud drum, two banks of tubes connected to the mud drum and divergently extending upwardly between the steam and water drums, and a steam super-heating drum arranged above the secondary combustion chamber in the path of the products of combustion issuing therefrom and connected to the steam and water drums.

upward therefrom, two steam and water drums arranged above the mud drum, one steam and water drum being connected to one bank of tubes and the other steam and water drum being connected to the other bank, means providing walls connecting each steam and water drum to the mud drum, rib tubes connecting each steam and water drum to the mud drum, said banks of tubes serving to divide the space between the drums and walls into three chambers, the chambers between the banks of tubes and the adjacent walls constituting initial combustion chambers and the chamber between the banks of tubes constituting a secondary combustion chamber, there being passages between the tubes of each bank permitting gases to pass therethrough from the initial combustion chamber into the secondary combustion chamber and to meet therein in opposition and revive or complete the combustion before passing upwardly between the steam and water drums, equalizing tubes connecting the steam and water drums across the top of the secondary combustion chamber between which the products of combustion from the secondary combustion chamber may pass.

10. A water tube steam boiler comprising a mud drum, two banks of tubes connected to the mud drum and divergently extending upward therefrom, two steam and water drums arranged above the mud drum, one steam and water drum being connected to one bank of tubes and the other steam and water drum being connected to the other bank, means providing walls connecting each steam and water drum to the mud drum, rib tubes connecting each steam and water drum to the mud drum, said banks of tubes serving to divide the space between the drums and walls into three chambers, the chambers between the banks of tubes and the adjacent walls constituting initial combustion chambers and the chamber between the banks of tubes constituting a secondary combustion chamber, there being passages between the tubes of each bank permitting gases to pass therethrough from the initial combustion chamber into the secondary combustion chamber and to meet therein in opposition and revive or complete the combustion before passing upwardly between the steam and water drums, equalizing tubes connecting the steam and water drums across the top of the secondary combustion chamber between which the products of combustion from the secondary combustion chamber may pass, and a steam super-heating drum arranged above said equalizing tubes and connected to the steam and water drums against which the products of combustion may strike after passing between the equalizing tubes. 125

In testimony whereof I have signed my name to this specification.

JOHN C. HANRAHAN.
